UNITED STATES PATENT OFFICE.

GROVER P. SHEARER, OF CHICAGO, ILLINOIS, ASSIGNOR TO A. L. RANDALL CO., OF CHICAGO, ILLINOIS, A CORPORATION OF ILLINOIS.

ORNAMENT AND METHOD OF MAKING THE SAME.

Application filed July 11, 1925. Serial No. 42,907.

To all whom it may concern:

Be it known that I, GROVER P. SHEARER, a citizen of the United States, residing at Chicago, in the county of Cook and State 5 of Illinois, have invented certain new and useful Improvements in Ornaments and Methods of Making the Same, of which the following is a specification.

This invention relates to improvements in 10 ornaments particularly adapted though not necessarily limited in its use for attachment to basket covers, box covers, wreaths and the like, and one of the objects of the invention is to provide an improved ornament which 15 will be of an artistic appearance and of a substantial construction.

A further object is to provide an improved 20 method for preparing a flexible strip or sheet to form the ornament and to impart rigidity and stiffness thereto when formed.

To the attainment of these ends and the accomplishment of other new and useful objects as will appear, the invention consists 25 in the features of novelty in substantially the construction, combination and arrangement of the several parts and in substantially the method hereinafter more fully described and claimed and shown in the accompanying drawing illustrating this invention, and in which—

Figure 1 is a top plan view of a cover for 30 a box or a basket having an ornament attached thereto constructed in accordance with the principles of this invention.

Figure 2 is a view of a portion of a strip used in the formation of the ornament.

In carrying this invention into operation 35 the ornament is formed of flexible material 10, preferably in the form of a strip or ribbon such as ordinary "gummed tape", heavy paper or any other suitable fabric of the desired weight and weave.

If the strip or piece of material employed 40 in the formation of the article is "sized" 45 the strip is immersed in water to soften the same to render it pliable and easy to manipulate.

The material thus softened is then shaped 50 to form a bow or any other ornament and may be then applied to a suitable support such as a cover 12, which is to be decorated and is fastened thereto in any suitable manner.

The support may also have secured thereto

in any suitable manner other ornaments 13, 55 which co-operate with the ornament 11 to render a pleasing appearance to the article or to decorate the same.

The support together with the bow or ornament 11 and the ornaments 13 are then 60 immersed in a strong sizing solution such as glue or the like, after which it is allowed to dry.

Water proofing material is then applied 65 to the ornaments in any suitable manner either by a dipping or spraying process, after which the article and the support therefor are allowed to dry. Coloring material may then be applied to the ornament.

If desired after the ribbon or strip has 70 been shaped into the ornament a coating of any suitable composition may be added which may be of any desired thickness to cause the same to appear as though it is 75 constructed of heavy material, and the ornament may then be applied to the support.

Obviously the coating may be of any desired thickness.

With this improved construction it will be 80 manifest that, as illustrated in the present invention, there will be produced a cover for a basket or box having an ornament applied thereto which will not only be of a pleasing appearance, but will be of a stout and comparatively rigid construction, which 85 will cause the ornament to maintain its shape and prevent the same from crushing under ordinary usage.

While the preferred method of constructing or forming the ornament has been herein 90 shown and described, it is to be understood that various changes may be made in the details of the operation of the method, without departing from the spirit of this invention. 95

What is claimed as new is:—

1. An ornament embodying a body portion of a ribbon like strip of flexible material looped and folded into shape upon and about itself and covered with a sizing to 100 render the same stiff and comparatively rigid.

2. An ornament embodying a body portion of a ribbon like strip of flexible material looped and folded upon itself to form a tied bow and having a coating of sizing to render the same stiff and comparatively rigid, and a coating of water proof material. 105

3. The method of constructing ornaments which consists in providing a ribbon like strip of flexible material, then immersing the same in water to render it pliable, then 5 while pliable looping and tying the material upon itself into a bow knot, then drying the shaped article, and applying a coating of sizing to the article to render the material stiff and comparatively rigid.
- 10 4. The method of constructing ornaments which consists in providing a ribbon like strip of flexible material, then immersing the same in water to render it pliable, then 15 while pliable looping and tying the material upon itself into a bow knot, then drying the shaped article, applying a coating of sizing to the article to render the material stiff and comparatively rigid, and then applying a water proof material.
- 20 5. The method of constructing ornaments which consists in providing a ribbon like strip of flexible material, then immersing the same in water to render it pliable, then 25 while pliable looping and tying the material upon itself into a bow knot, then drying the shaped article, then applying coloring to the ornament, and then applying a coating of sizing to the article to render the material stiff and comparatively rigid.
- 30 6. The method of constructing ornaments which consists in providing a ribbon like strip of flexible material, then immersing the same in water to render it pliable, then 35 while pliable looping and tying the material upon itself into a bow knot, then drying the shaped article, then applying coloring to the ornament, then applying a coating of sizing to the article to render the material
- stiff and comparatively rigid, and then water proofing the ornament. 40
7. As a unitary article of manufacture a comparatively rigid article of ornamentation the body of which is formed of a strip of pliable fabric like material looped about and upon itself into shape and stiffened with 45 a sizing solution and also having a water proof coating.
8. As a unitary article of manufacture a comparatively rigid article of ornamentation the body of which is formed of a ribbon like strip of fabric looped about and upon itself to form a bow or the like, and 50 coated with a sizing to render the same stiff and comparatively rigid.
9. As a unitary article of manufacture a comparatively rigid article of ornamentation the body of which is formed of a ribbon like strip of fabric looped about and upon itself to form a bow or the like, and 55 coated with a sizing to render the same stiff and comparatively rigid, the article being coated with a water proof material.
10. The method of constructing ornaments which consists in providing a ribbon like strip of flexible material, then subjecting the same to the action of moisture to render it pliable, then while pliable looping and tying the material upon itself to form a bow knot, and then applying a coating of sizing to the bow to render the material 60 stiff and comparatively rigid. 65
- 70 In testimony whereof I have signed my name to this specification, on this 8th day of July, A. D. 1925.

GROVER P. SHEARER.
